UNITED STATES PATENT OFFICE.

VIRGINIA JUDGE, OF SAN FRANCISCO, CALIFORNIA; DAN MALONE ADMINISTRATOR OF SAID VIRGINIA JUDGE, DECEASED.

DESIGN FOR A DOLL.

54,506.

Specification for Design.

Patented Feb. 17, 1920.

Application filed June 25, 1919. Serial No. 306,738. Term of patent 7 years

To all whom it may concern:

Be it known that I, VIRGINIA JUDGE, a citizen of the United States, residing in the city and county of San Francisco and State of California, have invented a new, original, and ornamental Design for a Doll, of which the following is a specification, reference being had to the accompanying drawings, forming a part thereof.

Fig. 2 is a view in rear elevation of the doll showing my new design.

I claim:

The ornamental design for a doll, as shown.

VIRGINIA JUDGE.

Witness:

W. W. HEALEY.
